AIRWAY SIGN

Filed Dec. 23, 1929

2 Sheets-Sheet 2

UNITED STATES PATENT OFFICE

EARL W. EDWARDS, OF CHICAGO, ILLINOIS

AIRWAY SIGN

Application filed December 23, 1929. Serial No. 416,181.

This invention relates to an improvement in airway signs.

The object of the invention is to provide an airway sign or marker of an improved character and one which may be practically installed for use in indicating the name or location of an air-port or field, or for other designations, or, if it should be desired, for advertising purposes.

10 The sign is preferably supported on the ground but elevated a substantial distance above the ground to an extent of from six to nine feet and in an approximately horizontal position. This reduces to a minimum the amount of trouble experienced in the construction and use of the sign. It is not obstructed or covered by snow, which will fall through the framework of the marker, except that which is actually deposited on the 15 letters, but the actual outline of the letters will always be visible.

By elevating the sign a substantial distance above its support, i. e., the ground, a roof, or the like, not only prevents its being 20 obstructed from view but also makes it possible to use the framework for other purposes, such as to enclose low roofed structures for tools, storage, rest rooms, or the like.

25 In the accompanying drawings:

Fig. 1 is a perspective view of the complete sign;

Fig. 2 is a longitudinal sectional view therethrough;

Fig. 3 is a disassembled perspective view of the parts of one of the supports;

Fig. 4 is a top plan view of the same; and

Fig. 5 is a vertical sectional view of the same.

The base of the sign may be suitably constructed of either metal, concrete or the like, sufficient to anchor the sign to the ground, the roof of a building or the like, and as a means of illustrating the invention this base portion is designated generally by the numeral 1, and is shown as inverted channel bars rigidly connected together and covered by sheet metal 2. However, this form of base 45 is not essential to the invention and is mere-

ly shown for purposes of illustrating its application.

This base 1 is securely fastened to the ground, the roof of a building or wherever the sign is to be used, and has base sockets 55 3 secured thereto for receiving posts 4. These posts are arranged preferably at the corners and at intermediate portions of the framework and are designed to support the sign itself. For this purpose they are provided 60 with heads 5 at their upper ends.

Each of the heads 5 has outwardly extending channel brackets 6 carried thereby for receiving the side rails 7 of the frame and intermediate rails 8, which serve to brace the 65 frame intermediate its ends, as shown in Fig. 1. The ends of the rails 7 and 8 are inserted into the channel brackets 6, as shown in Fig. 3, and are thus rigidly secured thereto to form a strong and substantial frame for supporting the letters of the sign.

Brace brackets 9 have the ends thereof received in the outermost channel brackets 6 and extend downwardly therefrom to receive a cable 10, which extends about the framework and is connected with these brackets 9 for bracing this framework.

The posts 4, which support the upper framework, are of a height sufficient to dispose the sign a substantial distance above the ground or other object on which it is carried, and this height should be from about six to ten feet, in order that the sign will be located sufficiently high so as not to be obstructed or covered by snow, dust, rain or the like, thus keeping it entirely free and clear at all times. The parts of the frame may be rigidly bolted together, rendering it strong and durable, and the frame may be entirely constructed of standard parts, thus simplifying its manufacture and construction and also substantially reducing the cost.

If desired, the sides of the frame may be enclosed with screen wire or other material 95 11 to keep persons or animals from interfering with the electrical equipment or other parts of the sign that may be within the enclosure. The sign will be sufficiently high from the ground or roof to enable small structures to be placed within the framework for 100

various purposes, such as storage of tools, rest rooms, or the like.

The sign characters, letters or the like, are designated by the numeral 12 and are designed to be supported upon and carried by the rails 7, being suitably secured thereto. Braces or supports 13 may be disposed beneath the sign characters or letters, if desired, not only to strengthen them but to facilitate the securing of them in place and to the framework. The upper surfaces of the characters may be colored as desirable or as required by proper regulations, and they are preferably illuminated also by any form of illumination, such as electric bulbs 14, as illustrated, or, if desired, by the use of neon lights or by reflected light.

The character of the illumination may depend upon the regulations governing the use of these signs, particularly where they are applied for indicating air-ports, cities or directional matter, particularly useful to pilots of aircraft.

The construction of the sign enables it to conform to regulations of the Department of Commerce or other governmental bodies, respecting the designation or illumination of air-ports or the like. It may be used not only for such designations but also for the designation of a town or city, or to give various directions and distances relative thereto, or, if desired, for advertising purposes.

The sign is thus supported in the horizontal position so as to be visible from substantial heights in the air for indicating to pilots of aircraft any of the various matters displayed thereon, and by reason of being supported in such elevated position and being open the sign characters are kept entirely free of obstruction in order to be fully visible. This prevents the accumulation of snow, rain, dust or other foreign matter on them at all times, which has been a great detriment to signs placed directly on the ground or the roof of a building.

I claim:

1. An airway sign comprising a framework having outer side members joined together, means for supporting said framework at a substantial height above the ground or other surface on which the sign is mounted, and sign characters fixed to said framework and extending across between the side members in approximately horizontal positions and approximately parallel with the surface on which the sign is supported, to be visible from aircraft at substantial heights.

2. A sign of the character described comprising supporting posts, heads carried by said posts, and having outwardly extending channel brackets carried thereby, frame members extending into and fixed to the channel brackets and forming a polygonal framework about the posts in approximately

a horizontal plane, and sign characters secured to said frame members.

3. A sign of the character described comprising a plurality of posts extending upwardly in polygonal shape, a head fixed to each of said posts and having laterally extending channel brackets on different sides thereof, rails fixed in said channel brackets and forming a polygonal framework about the posts, and extending approximately in a horizontal plane, and sign characters horizontally disposed upon and secured to said frame.

4. A sign of the character described comprising supporting posts, frame members carried by the posts and forming a polygonal framework, and extending approximately in a horizontal plane, and sign characters carried by said frame in an approximately horizontal position.

5. A sign of the character described comprising a base, upright supports carried by the base, frame members carried by the supports and extending in an approximately horizontal plane, and forming a polygonal framework about the posts, and sign characters horizontally disposed upon and secured to said framework.

6. A sign of the character described comprising supporting posts, a head fixed to each of said posts, and having laterally extending channel brackets on different sides thereof, frame members fixed to the channel brackets and forming an approximately horizontal supporting frame, sign characters carried thereby, brace brackets carried by the channel brackets on the outer sides of the posts, and bracing means connected with the brace brackets.

In testimony whereof I affix my signature.

EARL W. EDWARDS.
